UNITED STATES PATENT OFFICE.

WILLIAM G. WHITING, OF WALLINGTON, NEW YORK.

GAVEL-CARRIER FOR GRAIN-HARVESTERS.

SPECIFICATION forming part of Letters Patent No. 439,710, dated November 4, 1890.

Application filed July 7, 1890. Serial No. 357,930. (No model.)

To all whom it may concern:

Be it known that I, WILLIAM G. WHITING, of Wallington, in the county of Wayne and State of New York, have invented a new and useful Improvement in Gavel - Carriers for Grain-Harvesters, which improvement is fully set forth in the following specification and shown in the accompanying drawings.

My invention relates to self-binding grain-harvesters; and it consists in means and mechanism for carrying the gavel from the reaper-platform to a point at the side of the reaper, where it is presented to the binding mechanism.

It consists, also, in various other devices and parts constructed and arranged substantially as shown, the invention being herein-after fully described, and more particularly pointed out in the claims.

Referring to the drawings, Figure 1 is a plan of my invention with parts broken away and other parts shown in two positions by full and dotted lines; Fig. 2, a side elevation seen as indicated by arrow *x* in Fig. 1, the platform and base-board being sectioned, as on the dotted line *zz*; Fig. 3, a view of the parts seen as indicated by arrow *y* in Fig. 1, the platform being sectioned, as on the dotted line *x' x'* in said figure, parts being omitted. Fig. 4, viewed

the same as Fig. 3, shows other parts of the device; Fig. 5, the clutch mechanism of the driving-shaft. Fig. 6, drawn to a larger scale, shows the mechanism for turning the carrier, the wheel being in part sectioned. Fig. 7 shows the means for lifting the wind-guard. Fig. 8 shows the mutilated gears. Fig. 9, viewed the same as Fig. 3, shows the means for operating the outer compressor; and Fig. 10 a side elevation of the device for throwing

the machine out of gear.

Referring to the parts shown in the drawings, A is the platform of a reaper of common construction, curved to have the gavels cleared therefrom by an ordinary reel or sweep rake (not shown) in the usual manner.

B is a secondary platform on a plane a little below the platform A, consisting of a swing carrier for the gavel.

C is the base-board of the device. The carrier B is arranged to turn horizontally upon a vertical pivot *a* to the position shown in

dotted lines in Fig. 1, the grain being delivered upon said carrier from the platform A by means of the rake before the carrier starts.

The binding mechanism, which forms no 55 part of my invention, is located at the right of Fig. 1, D being the needle.

The moving parts of the device are operated by a driving-shaft *b*, which receives its motion from some convenient part of the driving mechanism of the reaper. A pinion *c* is fitted to the shaft *b* so as to slide longitudinally thereon, and is moved by means of a shifting mechanism *d*, having a crank-arm *e*. The shaft *b* turns loosely within the pinion, 65 and the latter turns with the shaft only when thrown against a pin *f* rigid with the shaft. (Shown in Fig. 5.)

g is a horizontal shaft held in the frame E, carrying a gear *h*, engaged by the pinion *c* to 70 drive said shaft. This shaft is also provided with a mutilated gear *i* and a bevel-gear *k*.

n is a shaft in the frame at right angles with *g*, in the same horizontal plane, provided with a bevel-gear *l*, engaged by the gear *k*, by 75 which said shaft *n* is turned.

o is a gear upon the shaft *n*, by means of which the binding mechanism may be driven.

p is a horizontal shaft held in the frame provided with a rigid pinion *r*, which is 80 turned at intervals by the mutilated gear *i*. This gear has as many teeth as there are teeth on the pinion, and the shaft *p* is turned and then rests while the blank part of the gear is passing the pinion, and then is turned 85 again. This intermittent motion of the shaft *p* causes the carrier B to swing out, rest, and return, and then it rests, waiting the collection of another gavel from being thrown out of gear.

s is a crank on the shaft *p*, connected by means of a pitman *t* to a horizontal reciprocating bar *u*, fitted to slide longitudinally in the frame. The pivot-shaft *a* of the carrier B is provided with a grooved wheel *v* beneath 95 the carrier, said wheel being tangent to the bar *u*, and a cable or cord *w*, making a turn around the wheel in the groove, has its ends crossed and secured to the bar at points respectively near its ends.

It will be seen 100 from this description that a single revolution of the crank *s* will cause the carrier to swing

away from the platform A and return. The extent of the horizontal motion of the bar u is made to equal about one-fourth of the circumference of the grooved wheel, so as to turn the carrier through about ninety degrees of arc.

a' is a retainer for the gavel on the carrier B, and b' is a discharger for the bound bundle. The retainer is pivoted to the shaft a , so as to swing in a vertical plane, and it serves to prevent the wind from disturbing the loose grain on the carrier. The discharger for the bundle is operated by a crank d' , rigid with the shaft n . A tortuous cam-lever e' , held to turn in a vertical plane upon a pin f' , rigid with the frame, is acted upon by the crank d' , so as to give the bundle-discharger an outward thrust at the proper time, as indicated by dotted lines in Fig. 3. As the crank encounters the lever, it pushes the latter rapidly outward until the point h' is passed, which gives the discharger its extreme outward motion. The lever is then quickly returned to its normal position by a spring i' , the crook in the lever causing it to be out of the way of the crank during the remainder of its revolution. A rigid rest k' is provided for the discharger, to hold the latter up out of the way of the carrier as the latter swings under it.

The lever e' while it acts to discharge the bundle at the same time lifts the retainer a' to allow the bundle to pass off the carrier. This it does by means of a projecting pin l' , bearing against the retainer, as indicated in Fig. 3, when the carrier brings the retainer over said pin.

n' are compressors for the gavel, held to turn on pins o' in the carrier. Springs p' , wound upon the respective pins and bearing against the compressors, tend to keep the latter thrown apart, as shown in Fig. 2. Beneath the carrier the compressors are provided with rollers t' , to follow curved tracks r' and s' , by means of which at the proper time the compressors are thrown toward each other, as shown in Fig. 4. This is when the gavel is about to be bound.

w' is a trip for the outer compressor n' . At its outer end the trip rests upon the bottom board C, and its inner end is held by a vertical lever v' , pivoted to the frame E, Figs. 3 and 9. At the upper end this lever is conveniently near the hub of the crank d' , which is provided with a projection w' to operate the lever. The outer end of the trip w' is contiguous with the extreme end of the track r' and forms a continuation of said track. When the carrier swings out to its extreme position and stops, the roller of the outer compressors rests against the trip, as shown in Fig. 9. Now, as the trip is moved outward by the action of the part w' and the lever v' , it carries the compressor to the right-hand position, (shown in dotted lines in said figure,) serving to further compress the gavel as it is being bound; but at this juncture the up-

turned end of the trip passes beyond the roller and frees the compressor, which is instantly thrown out to the left-hand horizontal position (shown in dotted lines) by the action of its spring p' . This is to permit the bound bundle to be pushed off the carrier by the discharger b' . When the carrier starts back to its normal position, the compressor rides upward along the curved rod or bow a^2 , Figs. 1 and 4. This brings it nearly to a vertical position or sufficiently erect to cause the roller to be caught by the branch b^2 of the track r' , and so as the carrier returns to place be brought, on account of the form of the track, to the position shown in Fig. 2. When the parts are all in their normal positions and at rest, the pinion c is disengaged from the driving-pin f , the crank-arm e of the shifting mechanism occupying the position shown in dotted lines in Figs. 1, 3, and 10. The rake (not shown) that carries the grain from the platform onto the carrier B encounters the arm e and turns it to the position shown in full lines in said Figs. 1, 3, and 10. This throws the pinion c over against the driving-pin f , which catches in the groove c^2 , Fig. 5, and sets the parts in motion. When the parts are at rest in their normal position, the middle tooth of the mutilated gear i is engaged with the pinion r , so that when the pinion c is thrown into gear, as just above stated, the pinion r is immediately turned through a half-revolution by the gear. This moves the carrier out to the position shown in dotted lines in Fig. 1. At this juncture the blank part of the gear i reaches the pinion r , and the motion of the carrier ceases during the passage of said blank part by the pinion. It is during this dwell of the carrier that the above-described actions of the trip w' and the discharger b' take place and the binding of the bundle is accomplished. When the gear i again presents its teeth to the pinion r , (see Fig. 8,) the latter is turned through another half-revolution, or until the carrier is brought to its normal position of rest next the platform. As the carrier is approaching this position of rest, the pinion c is automatically thrown out of gear or away from the pin f by the following means: d^2 , Figs. 1 and 10, is a rod held to slide horizontally in a standard e^2 , rigid with the carrier, to bear against the crank-arm e . The rod is provided with a spring f^2 to urge it forward against the crank-arm, and further formed with an extended part g^2 to move along a guide h^2 , also rigid with the carrier. This rod is so placed that when the carrier is returned to place it encounters the crank-arm e and throws it over to the position shown in dotted lines, in which the pinion c is thrown back from the driving-pin f . All the parts will then remain at rest and be inoperative until the rake, as above described, encounters the crank-arm and again throws the pinion into gear. When the rake moves the crank-arm to the position shown in full lines, it does so against the action of the spring f^2 , but the

yielding of the spring admits of this, while the action of the spring unopposed is capable of throwing the crank-arm over, as above described, to disengage the pinion *c*.

5 The crank-arm is secured to a rod *i*², Figs. 1, 2, and 4, beneath the platform. A hook *k*², hinged to the under side of the platform, reaches out under the carrier *B* to engage a boss *l*² rigid with the carrier. The shaft is 10 beneath the hook and provided with an arm *n*² to bear against the hook. Now, when the rod *d*² turns the crank-arm, as above described, it raises the hook so as to engage the boss and so hold the carrier steady with reference to the platform while the carrier is at 15 its normal position. When the rake turns the crank-arm, it allows the hook to fall away from the boss and thus release the carrier.

The crank *s*, Fig. 2, is formed with a slot *s*², 20 in which to receive the pin *o*², so the latter may be adjusted to give to the carrier a greater or less extent of swing. This is for the purpose of presenting the gavel to the binder, so the band may be put thereon nearer to or farther from the heads, as may be desired.

What I claim as my invention is—

1. An attachment for a self-binding harvester, consisting of a horizontally-moving carrier for the gavel, a wheel rigid with the 30 carrier, a reciprocating rod to turn the wheel, and means for operating said reciprocating rod, in combination with a compressor for the gavel held by the carrier, and a discharger for the bundle held on the frame of the machine, substantially as described.

2. An attachment for a self-binding harvester, consisting of a horizontally-moving carrier for the gavel, a wheel rigid with the carrier, a reciprocating rod to turn the wheel, 40 and means for operating said reciprocating rod, in combination with a compressor for the gavel held by the carrier, a discharger for the bundle held by the main frame, and a wind board or retainer for the gavel located on said carrier, substantially as described and shown.

45 3. A harvester attachment consisting of a

swinging carrier for the gavel, provided with a wheel, a reciprocating rod to turn the wheel, and means for operating the rod, in combination with compressors for the gavel held 50 by the carrier, a trip for the outer compressor resting on the bottom board of the frame, and an erector for said outer compressor held by said bottom board, substantially as described.

4. A harvester attachment consisting of a 55 swinging carrier for the gavel, a wheel, and reciprocating rod to turn the carrier, with crank and pitman to operate the rod, in combination with a driving-clutch, a shifter for said clutch, and an operating device for said shifter held by said carrier, substantially as 60 and for the purpose set forth.

5. An attachment for a self-binding harvester, consisting of a carrier for the gavel held to turn in vertical bearings, a grooved 65 wheel rigid with the carrier, a reciprocating rod to turn the wheel, and a cord or cable held by said rod to encircle the wheel, in combination with a crank and a pitman to reciprocate the rod, substantially as described.

6. In combination with the platform of a self-binding harvester, a swinging carrier for the gavel, a catch or hook to hold said platform and carrier together, a shaft to operate said catch, an arm rigid with said shaft, and 70 an operator for said shaft secured to said carrier, substantially as described.

7. A rotatory shaft *n* of a self-binding harvester, provided with a crank *d*', and a pivoted carrier for the gavel, in combination with 80 a cam-lever operated by said crank, a reciprocating discharger for the bundle operated by said cam-lever, and a rigid rest for said discharger, substantially as and for the purpose specified.

In witness whereof I have hereunto set my hand, this 2d day of June, 1890, in the presence of two subscribing witnesses.

WILLIAM G. WHITING.
